UNITED STATES PATENT OFFICE.

FRANK B. GLOVER, OF BROOKLYN, NEW YORK.

MULTIPLE ENGRAVING MACHINE.

Application filed October 1, 1920. Serial No. 414,107.

To all whom it may concern:

Be it known that I, FRANK B. GLOVER, a citizen of the United States, residing in Brooklyn, in the county of Kings and State of New York, have invented certain new and useful Improvements in Multiple Engraving Machines, of which the following is a specification.

The main purpose of this invention is to provide an engraving machine in which a plurality of like articles are simultaneously engraved in a uniform manner.

Another object is to provide means for independently adjusting the articles to bring a definite point into known relation with the scribe prior to engraving.

A further object is to provide means for raising and lowering the scribes as they are moved from one character to another.

These and other objects, tending to accuracy, efficiency and simplicity, as will become manifest as the description proceeds, are attained by the novel construction, combination and arrangement of parts, herein-after described and shown in the annexed drawings, forming a material and essential part of this disclosure, and in which:—

Figure 1 is a front elevational view of an engraving machine made in accordance with the invention.

Figure 2 is a top plan view of the same.

Figure 3 is a rear elevational view thereof.

Figure 4 is a partial side elevational and sectional view, the section being taken on line 4—4 of Fig. 1.

Figure 5 is an enlarged fragmentary view showing a scribe in operative position.

Figure 6 is a fragmentary view showing a section of the work frame slide and its operating means.

Figure 7 is a fragmentary perspective view of a template.

Figure 8 is a perspective view showing the scribe bar holder frame and its mountings.

Figure 9 is a side elevational view of the frame actuating device.

Figure 10 is a front side view of a thermometer, drawn to an enlarged scale and showing the work for which the machine is specifically designed.

Figure 11 is a perspective view of one of the pairs of work holding clamps showing its mounting.

Figure 12 is a perspective view of a key

device for actuating all of the work-holders on one side of the frame simultaneously.

The machine illustrated is particularly designed for operating on glass tubes, as used for thermometers, upon which are inscribed numerals and other characters with reference to their scales, and similar inscriptions, involving accuracy, duplication and rapidity.

These tubes are coated previously with a suitable composition adapted to resist the erosive effects of a bath in the acids used to etch the characters directly into the glass, through the marks made in the coating by the stylus, which are guided by a template in the manner of a pantograph.

Referring to the drawings in detail, the machine will be seen to include a level base plate or platform 25 supported at a convenient height by any suitable means, as for instance, the pedestal or column 26.

Secured on the upper surface of the platform, parallel to and adjacent its front edges, are a pair of spaced parallel rails 27 receiving between them a template or plate 28 acting as a guide and having engraved characters of different sizes arranged in grouped relation as indicated by the reference characters 29 and 29' and other indicia 30, as shown best in Figures 2 and 7.

An undercut groove or slot 32 is formed in the platform parallel to its front edge and rearward of the rails, the same having fitted to it a slide 33, the purpose of which will be further explained.

The slide 33 has secured to its under side a rack 34 engaging the teeth of a gear 35 fixed on a spindle 36 mounted transversely in lugs below the platform and provided with an operating knob 38 readily accessible to an operator at the front of the machine.

Fixed upon the platform, near the rear, are a pair of posts 40, connected at their upper ends by bolts with a rigid arched tie beam 41, having at its central highest portion lateral hubs bored to slidably receive a level cylindrical bar 42 provided with a slot 43 receptive of the point of a knurled headed clamp screw 44 operable from the top of the beam.

Formed integral with the front end of the bar, 42 are a pair of spaced, downwardly extending lugs 45 and 45', carrying conical pointed set screws 46 and 46' provided with check nuts for holding them when in ad-

justment, and pivotally mounted on the points of the screws is a spindle 47 from which extend the elements of a clevis yoke 48, provided at its opposed ends with pivot pointed set screws 49 and lock nuts as shown.

Engaged by the points of these screws is the upper end of a stiff vertical pendulous bar 50 comprised of a pair of side rails integrally connected by cross members.

Carried at the lower end of the bar 50 are pivot screws 51 provided with lock nuts and engaging the rear end of a normally central, forwardly extending arm 52, in the front end of which is removably carried a stylus or pointer 53 adapted to engage in the characters of the template 28 as best shown in Figs. 2 and 4.

A slide 55 is fitted to operate on the rails 20 of the bar 50, the same being clamped, when in adjustment, by a plate 56, through which passes a bolt 57, fixed in the slide and provided with a winged nut 58 and washer 59.

A pair of opposed, rearwardly extending 25 lugs 60 are formed with the slide, receptive of the pivot points of set screws 61 passing through the ends of a clevis yoke 62 and provided with lock nuts as shown.

A hub 63 is formed with the connecting 30 element between the clevis ends and from it extends an integral sleeve 64, bored to rotatably receive a spindle 65 having a shoulder near its front end held in contact with the end of the sleeve by adjustable lock nuts 66.

Beyond the shoulder is a head 68 bored 35 and internally threaded at a right angle to the axis of the spindle, receptive of plugs 69 and 70, respectively upper and lower, having concave seats adapted to receive the spherical head 71 of a rod 72 passing freely 40 down through an appropriate opening in the plug 70. The plugs 69 and 70 both have enlarged flange-like heads drawn tightly against the respective ends of the element 68 by reason of their screw threaded bodies and thus should the spherical head 71 become loosened by wear it is an easy 45 matter to adjust the same in its bearings.

This arrangement, in practice, has been 50 found to produce highly satisfactory results unattainable by ordinary gimbal joint connections.

A pair of opposed uprights 75 are bolted 55 to the platform 25 and secured to their inner faces, respectively near their tops and bottoms, are pairs of short horizontal rails 76 and 77, extending parallel to the faces of the upright and being grooved longitudinally to act as races or tracks for the balls 60 78, held in operative position by pins 79 or like spacing elements.

Other grooved rails 80 and 81 engage the 65 balls upon their opposite sides and are connected in pairs by integral bars 82 and 83, the same being grooved lengthwise in their

outer surfaces and adapted to receive other balls 84, supporting and guiding grooved bars 85 and 86, connected to form an open, rigid rectangular frame, by pairs of inner and outer vertical bars respectively 87 and 88 and 87' and 88' having between them the bars 82 and 83, the structure being shown in detail in Fig. 8.

A rigid flat open frame 90 having pads 91 extending laterally from its ends, is fastened by them to the rear bars 87' and 88' of each pair and extending rearwardly from the central element of the frame are lugs 92 provided with set screws for clamping the rod 72 adjustably and rigidly therein.

From the foregoing it will be apparent that maneuvering the arm 52 in accordance with the template causes the frames to move on their frictionless supports, backward or forward and to either side in exact conformity, but to a lesser degree, according to the position of the clevis yoke 62 relative to the length of the pendulous bar 50, through the gimbals and slides mentioned, but that the frames are not raised or lowered.

The bars 87-87' and 88-88' extend above the frame and are connected at their tops by plates 95 in which are set-screws 96 their points impinging on the bars 85, thus adjusting the tension or pressure on the balls 84.

The extending ends of the bar 85 have secured to them Z shaped brackets 98 carrying adjustable screws 99 used in supporting magnets 100 provided with armatures 101 carried on rods 102 guided in brackets 103 also attached to the frame bar 85.

The rods 102 are fixed in the tops of vertical bars 105 extending down behind the cross bar 86 to which is attached rearwardly extending strips 106 carrying upright slide plates 107 attached by screws 108 or the like passing through slots 109 formed in the stops, the ends of the rods being guided in openings in the strips 106.

Fixed in the inner sides of the bars 105 are a plurality of pins 110 extending sufficiently to act as lateral guides for lever bars 111 pivoted between the rear pairs 87' and 88' of the vertical bars on pins 112, and extending, at their rear ends below and in close proximity to the pins 110.

The front ends of the lever bars 111 are drilled to receive stems 113 formed with heads 114 in which the scribes 115 are adjustably secured. Pins 116 fixed in the front ends of the scribe bars are used to secure weights 117 by which moderate pressure on the scribe points may be adjustably applied.

Another pair of standards 120 and 121 are bolted to the slide 33, the standard 120 carrying hinge elements 122 and 123, the latter having a stop 124. These elements

receive corresponding hinge elements 126 and 127 fixed upon the side strip 125 of a swinging frame, this strip being connected by rigid bars 128 and 129 with the 5 mating front strip 130 forming the four sides of the frame which may be secured, when in a closed position between the standards, by a pair of buttons 132 pivoted on pins 133 set in the standard 121 and operated in unison by a connection rod 134 pivoted to the outer ends of the buttons and provided with an actuating handle 135 by which the buttons are operated.

15 A plurality of rack bars 138 having downwardly extending teeth are attached at their ends respectively to the frame side strips 125 and 130 and are also connected by a central vertical bar 139 fixed at its upper end to the top transverse element 128 of 20 the frame, as best shown in Fig. 1.

25 Slidably disposed over the tops and sides of the rack bars are casings 140, their side elements having lugs 141 receptive of transverse spindles 142, actuated by extending knurled knobs 143 and carrying pinions 144 30 engaging the teeth of the rack so that the casings may be easily and definitely moved longitudinally of the racks.

35 Slidable on the casings are pairs of work 30 holders or clamps each consisting of a body 145 having a narrow rearwardly extending jaw or lug 146 at the top and a full width projection 147 therebelow. At the front a pair of down turned lugs 148 carrying pivot pins 149 on which are mounted levers 150, passing below the rack bars and connecting with the stems 151 of V blocks 152.

40 These stems are guided in openings appropriately formed in the projections 147 so that the blocks, which constitute lower jaws, are in register with the fixed upper jaws 146 and are movable towards or from them by the levers 150.

45 The outer ends of these levers are drilled to receive the cylindrical ends 155 of a square bar 156 on which is mounted a flat spring 157 raised at its center and held by screws passing through slots 158 near its 50 ends, thus permitting the spring to yield under pressure as applied by the cam 160.

55 The cam is fixed to the lower end of a vertical spindle 161 rotatable in brackets 162, formed with or secured to the casing 140 and provided with an operating hand lever 163 by which the cam is rotated.

60 From the foregoing it will be seen that the work holders, comprised of elements 140-163 may be moved along the rack bars 138 into any desired position with reference to the scribers 115; that the blocks or heads 145 are independently adjustable on the casting, towards or from each other, thus providing for work parts of varying lengths, 65 and that the jaws 152 are simultaneously

70 moved to clamp work against the fixed jaws 146, which being level, always present the upper surface of the work at a uniform plane, irrespective of variations in its diameter.

75 It will further be noticed that pressure is equally applied to each pair of jaws and through the intermediary of a spring so as to avoid crushing or other damage to the work parts, as exemplified by the thermometer tube 200, shown in detail in Fig. 10 and in broken lines in Figs. 1 and 2.

80 As has been described, these several work holder support racks are fixed in tiers horizontally in frames comprised of elements 125-130 and secured by hinges in such manner as to permit complete separation from the uprights 120-121, thus affording opportunity for one of the frames to be charged with the work parts while another 85 frame is being operated in the machine. In certain classes of work, as for instance inscribing names, etc., where the inscription does not refer to any exact point on the work surface, the device shown in Fig. 12 90 may be used.

95 This consists of a bar 170 having lateral projections 171 containing aligned openings 172 adapted to engage the work holder clamp elements 163 so that all of the several work holders upon one side of the frame can be simultaneously operated, it being understood that in this case the several spindles 161 are in vertical alignment.

100 After the tubes or other work parts have been clamped in their holders their support frames are placed upon the hinge elements 122-123, swung into operative position, and clamped by operating the handle 135, whereupon the work parts are adjusted by moving the work holders longitudinally on the rack bars so that certain definite points previously indicated upon the tube are brought into vertical registration with the scribers.

105 The desired character on the template 28 as the numeral 8, (see Fig. 2) having been brought into an approximately central position relative to the machine, though not absolutely necessary, the bar 52 carrying stylus 53 is grasped by an operator at a point near the head carrying the stylus so as to conveniently and easily guide and manipulate the same and is then placed in 115 the lines of template.

120 Due to the gimbal joints and freely swinging connections used, the movement of the stylus is accurately conveyed, but in a reduced degree, to the frame 90 and thence to the scribe bar carrying frame, which is mounted to move without friction, in a level plane, in any direction, thus causing the scribers to faithfully follow the movement imparted to the stylus.

125 The amount of reduction of movement is 130

adjustably controlled by the position of the slide 55 upon the pendulous lever bar 50, relative to the distance from its pivotal support point and proportional to its length, the rod 72 being correspondingly adjustable in the lugs protruding from the frame 90.

All of the several stylii and their supporting frames are adjustable to or from the centers of the work jaws by movement of the cylindrical bar 42 within its arched support, thus simultaneously changing their vertical plane as may be desired to accommodate different shapes of work.

A source of electrical energy, as a storage battery 170 is provided to energize the magnets 100, a push button switch 172 being located on the platform 25, stylus bar, or on the floor, where it can be conveniently reached by an operator to control the circuit.

The scribe bars 111 are so pivoted as to cause their front ends, which carry the scribes, when approximately level, to operatively engage the surfaces of the work parts, the position of the armatures 103 being against the ends of the magnets when engraving, but when it is desired to shift the scribes from one character to another, the button switch is released, causing a break in the current and consequently freeing the armatures which, dropping down by gravity, carry the bars 105, their pins 110 striking and tilting the scribes simultaneously up from the work.

Although electro-magnet means have been described and shown as used for raising and lowering the stylii, it will be apparent that a wide range of mechanical devices may be substituted which will operate effectively and quickly in producing the same results and which are not precluded from use.

It is also to be understood that any of the commercial forms of pantographs may be substituted for the elements 25 to 55 as herein described without conflicting with the principal characteristics of the invention and which would not be beyond the ability of a mechanic to change so as to be used in connection with the remaining and more consequential elements.

From the foregoing it will be seen that the operation of the machine is efficient and rapid as well as accurate, and also that a plurality of similar work pieces can be operated upon at the same time without difficulty.

It is not desired, however, to be confined strictly to the specific mechanical parts as described, as under the spirit and scope of the invention, mechanical equivalents may be substituted and variations made without departing from the general intention of the invention.

What I claim as new and desire to secure by Letters Patent, is:—

1. An engraving machine comprising a

frame having a plurality of scribes therein, means for actuating the scribes simultaneously, and means for collectively raising said scribes, said means permitting raising the scribes independently. 70

2. An engraving machine comprising a frame having a plurality of scribes therein, means for actuating the scribes simultaneously, and means for differentiating the pressure of said scribes individually upon 75 the work surfaces.

3. An engraving machine comprising a frame having a plurality of scribes operable uniformly in the same vertical plane therein, work holders adjacent each scribe, means for raising all of said scribes in unison, said scribes normally descending by gravity, and a single means for guiding said scribes. 80

4. An engraving machine comprising a fixed supports carrying a floating frame having a plurality of scribes movable therein, means for producing uniform simultaneous action thereof, a frame removably engaged to said fixed supports, work holders in said removable frame, and means for adjusting each holder relative to its corresponding scribe. 85

5. An engraving machine comprising fixed supports, a floating frame therein, carrying a plurality of scribes, means for producing uniform simultaneous action of said scribes, a frame hingedly engaged to said fixed supports, means for clamping said removable frame in operative position, a series of duplex work holders, and means for independently adjusting said holders longitudinally in the floating frame. 95 100

6. An engraving machine comprising fixed supports carrying a floating frame having a plurality of scribes movable therein, means for actuating the scribes simultaneously, an interchangeable work holding frame hingedly engaged in said supports, and a single means for clamping said frame at points opposite the hinges. 105 110

7. An engraving machine comprising a floating frame having a plurality of scribes movable therein, a single means for actuating all of said scribes uniformly, and a guide template for said actuating means, said scribes being so mounted as to permit shifting collectively transversely to said guide template. 115

8. An engraving machine comprising fixed supports having a movable frame having a plurality of scribes movable in said frame, a single means for actuating all of said scribes uniformly, a guide template for said actuating means, a slideway longitudinally disposed on said frame in which said guide template can be adjusted, and means for collectively adjusting said scribes relative to said guide template laterally. 120 125

9. An engraving machine comprising a 130

- movable frame having a plurality of scribes acting in unison, a single guide template therefor, a work carrying frame removably engageable with said fixed frame, rack bars arranged in tiers horizontally in the work carrying frame, work holders slidable on said bars, and means for adjusting the work holders with respect to said scribes.
10. An engraving machine comprising fixed supports, a frame floatingly mounted therein having a plurality of scribes operably in unison, a single template therefor, a universally movable support in said frame upon which said scribes are pivoted, said support being movable in a level plane in any direction, stops for said scribes and means for raising said scribes upon their pivots.
11. An engraving machine comprising a floatingly mounted frame having a plurality of scribes operable in unison, a single guide template therefor, a work frame engageable with the supports of said floating frame, a plurality of work holders carried by said work frame, means for independently adjusting said work holders in the work frame, and means for moving said work frame and holders lengthwise.
12. An engraving machine comprising a platform, an arched support at the rear of said platform, a horizontal yoke bar adjustable in said support, a universal gimbal mounted in the yoke bar, a pendulous lever suspended by said gimbal, a stylus carrying arm pivoted at the bottom of said lever, means for guiding the stylus, and a plurality of scribes operated by said lever in conformity with the movement of the stylus.
13. An engraving machine comprising a support, a lever mounted at its upper end in said support to move in any direction, a manually operable arm hingedly engaging the lower end of the lever, a stylus adjustably carried by said arm, a movable guide for said stylus, a slide adjustable on said lever, a floating frame operated by said slide supports for said frame and a plurality of scribes carried in said floating frame.
14. An engraving machine comprising a platform, a slide movable lengthwise of the platform, standards fixed on said slide, a frame hinged to one of said standards, a single means for clamping said frame to the other standard, and a plurality of work holders mounted in vertical rows independently movable lengthwise in said frame.
15. An engraving machine comprising a platform, a vertical lever suspended by gimbal over said platform, an arm pivoted in a horizontal plate to said lever, a stylus carried at the end of said arm, a guide for said stylus adjustable at the front of the platform, a plurality of scribes operated by said lever, and means for adjusting the movement of said scribes relative to the stylus.
16. An engraving machine comprising a platform, a slide, a pair of uprights fixed thereon, a frame universally movable in horizontal directions, said frame having horizontal elements extending at each of its corners to the front and rear, corresponding elements fixed on said uprights, all of said elements being grooved to receive anti-friction balls, means for adjusting the pressure on the balls, and means for imparting motion to said frame.
17. An engraving machine comprising a platform having a slide, uprights on said slide, standards fixed on said platform, a plurality of work holders removably engaged in the standards, a frame floatingly held by said uprights, stylus carrying bars pivotally supported and guided in said frame, the stylii carried thereby corresponding to said work holders, means for tilting the bars on their pivots, and means for manually actuating the frame in accordance with a temperature whereby the stylii are caused to travel predetermined paths.
- An engraving machine comprising a plurality of scribe carrying bars arranged in vertical rows, means for pivotally supporting and guiding said bars, means for tilting the bars upon their pivots whereby the scribes are raised or lowered, a frame anti-frictionally mounted in which said bars are mounted, and means for moving said frame whereby the scribes are caused to travel a given path simultaneously.
19. An engraving machine comprising a platform, a support thereon, a universally mounted pendulous lever adjustably carried in said support, means for controlling the movement of said lever, a slide engaging said lever, a clevis yoke connecting with said slide, a tubular extension formed with the yoke, a bar rotatable in said extension, said bar having a head, a frame mounted to move universally in a level plane on the platform, scribe bars pivoted in said frame, a rod adjustably secured in said frame, said rod having a spherical end, and means for holding said spherical end in the head of said bar.
20. An engraving machine comprising a plurality of scribe carrying bars arranged in paired relation in vertical rows, a frame having pairs of vertical bars between which said scribe bars are guided, pivotal supports carried by certain of said vertical bars in each pair for said scribe bars, other vertical bars carrying lateral pins adapted to make contact with the rear ends of said scribe bars, means for holding the last named bars in a raised position whereby the scribes are permitted to make operative contact with the work, means for raising the scribes simultaneously, and means for actuating said frame in any direction horizontally.

21. A work holder comprising a frame having a support, means for moving said frame longitudinally thereon, duplex heads 5 slidable on said frame, fixed and movable jaws in said heads, and means carried by said frame for actuating the movable jaws of each head simultaneously.

22. A plurality of work holders each having a pair of fixed and movable jaws, a single operating means for each pair of the movable jaws, and means for simultaneously actuating said operating means.

23. A work holder comprising a slidably mounted frame, heads independently slidable on said frame, fixed and movable jaws carried by said heads, levers for operating said movable jaws, a bar engaging both levers, a cam adapted to exert pressure on said bar, means for actuating said cam, and

a spring interposed between said cam and 20 bar.

24. A work holder comprising a frame, a rack bar on which the frame is mounted, means including a pinion for moving said frame on the bar, duplex head 25 slidably mounted on said frame, jaws having level lower surfaces extending rigidly from said heads, grooved jaws movable vertically in said heads relative to the fixed jaws, actuating levers for movable jaws, a single bar 30 engaging each pair of levers, and means for exerting pressure on said bar whereby said movable jaws are moved simultaneously towards the fixed jaws.

In testimony whereof I have signed my 35 name to this application.

FRANK B. GLOVER.
